CLAIM

The ornamental design for a steering wheel for a motor vehicle, as shown and described.

DESCRIPTION

FIG. 1 is a front perspective view of a steering wheel for a motor vehicle showing our new design;

FIG. 2 is a front and right side perspective view thereof;

FIG. 3 is a rear perspective view thereof;

FIG. 4 is a rear and left side perspective view thereof;

FIG. 5 is a front elevational view thereof;

FIG. 6 is a rear elevational view thereof;

FIG. 7 is a left side elevational view thereof, the right side being a mirror image thereof;

FIG. 8 is a top plan view thereof; and,

FIG. 9 is a bottom plan view thereof.

The broken lines shown throughout the drawing views are for illustrative and environmental purposes and form no part of the claimed design.
